Primary Examiner — Marianne Pandozzi(74) *Attorney, Agent, or Firm* — Warner Norcross & Judd LLP(57) **CLAIM**

The ornamental design for a hot water dispenser, as shown and described.

DESCRIPTION

FIG. 1 is a top, right, front perspective view of a hot water dispenser;

FIG. 2 is a top, left, front perspective view thereof;

FIG. 3 is a bottom, left, front perspective view thereof;

FIG. 4 is a left side view thereof;

FIG. 5 is a front view thereof;

FIG. 6 is a right side view thereof;

FIG. 7 is a rear view thereof;

FIG. 8 is a top plan view thereof; and,

FIG. 9 is a bottom plan view thereof.

FIGS. 1-9 show portions of the hot water dispenser in broken lines. The broken line portions are shown for environmental purposes and form no part of the claimed design. The broken line segments immediately adjacent the solid line portions of the design define the boundary of the design, but do not themselves form part of the claimed design.
